SAFETY CIGAR COVER

Nicola Farinella, New York, N. Y., assignor to
Concettina Farinella, New York, N. Y.

Application May 16, 1935, Serial No. 21,783

2 Claims. (Cl. 206—41)

This invention relates to new and useful improvements in a safety cigar cover.

The invention has for an object the construction of a device as mentioned which is characterized by a hollow fireproof container of cigar shape and consisting of a body section and a cap section having inter-engageable ends for holding the cover closed.

A feature of the invention resides in the fact that a cigar which has only been partially smoked may be stored within the safety cigar cover and saved for future use.

A further object of the invention is an arrangement whereby one of the sections is formed with a bead controlling the inter-engagement of the sections when the cover is closed.

Still further the invention proposes the association of a clip with the safety cigar cover so that it may be clipped upon the material of one's pocket and assist in preventing accidental loss.

Still further the invention contemplates the provision of a removable and replaceable lining within the safety cigar cover for sanitary purposes.

25 Another object of the invention is the provision of finger elements upon the lining and adapted to coact with certain openings and hollows upon portions of the safety cigar cover by which the lining is replaceably held in position.

30 Another object is the construction of an article as described which is simple and durable and which can be manufactured and sold at a reasonable cost.

35 For further comprehension of the invention, and of the objects and advantages thereof, reference will be had to the following description and accompanying drawing, and to the appended claims in which the various novel features of the invention are more particularly set forth.

40 In the accompanying drawing forming a material part of this disclosure:—

Fig. 1 is a perspective view of a safety cigar cover constructed according to this invention.

45 Fig. 2 is a sectional view taken on the line 2—2 of Fig. 1.

Fig. 3 is a side elevational view of a safety cigar cover constructed according to another embodiment of the invention.

50 Fig. 4 is a perspective view of the cap portion of a safety cigar cover constructed according to a still further embodiment of the invention.

Fig. 5 is a sectional view taken on the line 5—5 of Fig. 4.

55 Fig. 6 is a bottom elevational view of Fig. 5.

Fig. 7 is a similar view to Fig. 2, but illustrating a modified form of the invention.

The safety cigar cover, according to this invention, comprises a hollow fire proof container 10 of cigar shape and consisting of a body section 10^a and a cap section 10^b having inter-engageable ends 10' and 10'', respectively, for holding the cover closed. The end 10'' has an exterior diameter adapted to fit the interior diameter of the end 10'. One of the sections forming the container has a circumferential bead 11 spaced in slightly from the end thereof and adapted to limit the inter-engagement of the sections. The exterior of the container is imprinted or engraved with an ornamental design 12. 15

In Fig. 3 a modification of the invention has been disclosed wherein a hollow fireproof container 10 is illustrated and which distinguishes from the preferred form in the provision of a clip 13 by which it may be clipped upon the material of one's pocket. 20

More particularly, the clip 13 is attached upon the clip section 10^b of the safety cigar cover. The container 10 is inscribed, imprinted or engraved with an ornamental design 12'. In other respects, this form of the invention is identical to the previous form and corresponding parts may be recognized by the identical reference numerals. 25

In Figs. 4—6 inclusive another embodiment of the invention has been disclosed which distinguishes from the prior forms by the provision of a removable and replaceable lining 15 arranged in the cap section 10^b. This lining, preferably, should be of flexible fire-proof material, 35 or paper. The edge of the cap section 10^b is formed with a pair of diametrically opposite openings 16 having enlarged base portions 16^a. The material of the end 10'' immediately below the base portions 16^a of the openings is bent or 40 concaved inwards, as clearly shown in Fig. 5 of the drawing. The lining 15 has a pair of diametrically opposite finger elements 15^a of a width corresponding with the width of the base portions 16^a of the openings 16. The arrangement 45 is such that the finger elements 15^a may be forced through the openings 16 until they reach positions in the base openings 16^a. They serve to hold the lining against displacement. The finger portions 15^a are adapted to engage within the hollows beneath the base portion 16^a of the openings so that the outer faces of the fingers, when 50 bent downwards are flush with the surface of the end 10''. Thus, there is no obstruction to the 55

proper engagement of the cap section upon the body section of the cigar cover.

In Fig. 7 the body section 10^a and the cap section 10^b are shown joined with threaded inter-engageable ends 10^c and 10^d, respectively.

It is to be understood that the size, shape and material of "safety cigar cover" may be changed as desired.

In use, a cigar may be carried safely in one's pocket when housed within the safety cigar cover. The cigar may be smoked for any period of time, and if not entirely consumed may be temporarily stored in the safety cigar cover.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A safety cigar cover, comprising a hollow fire-proof container of cigar shape and consisting of a body section and a cap section having

inter-engageable ends for holding the cover closed, and a removable and replaceable lining within the cap section of said cover, said lining having a pair of finger portions upon the edge thereof engaging through openings formed in from the edge of the cap section and disposed within enlarged base portions of said openings, and the material of the cap section immediately below the enlarged base portions of the openings being concaved inwards to form hollows in which said finger portions are engaged. 5

2. A safety cigar cover, comprising a hollow fire proof container of cigar shape, and consisting of a body section and a cap section having 15 inter-engageable ends for holding the cover closed, and a removable and replaceable lining within the cap section of the cover, said lining having a pair of finger portions upon the edge thereof engaging through openings formed in 20 from the edges of the cap section, and the material of the cap section immediately below said openings being concaved inwards to form hollows in which said finger portions are engaged. 25

NICOLA FARINELLA.
